UNITED STATES PATENT OFFICE.

HENRY C. SERGEANT, OF WESTFIELD, NEW JERSEY, AND WILLIAM PRELLWITZ, OF EASTON, PENNSYLVANIA, ASSIGNEES TO THE INGERSOLL-SERGEANT DRILL COMPANY, OF NEW YORK, N. Y.

DIRECT-ACTING ENGINE.

SPECIFICATION forming part of Letters Patent No. 679,999, dated August 6, 1901.

Application filed February 21, 1901. Serial No. 48,273. (No model.)

To all whom it may concern:

Be it known that we, HENRY C. SERGEANT, a resident of Westfield, in the county of Union and State of New Jersey, and WILLIAM PRELLWITZ, a resident of Easton, in the county of Northampton and State of Pennsylvania, citizens of the United States, have invented a new and useful Improvement in Direct-Acting Reciprocating Engines, of which the following is

10 a specification.

This invention relates more particularly to direct-acting reciprocating engines such as are used in what are variously known as "coal-cutting machines" or "coal-picks," in

15 which the engine-piston carries a pick or tool which operates by a direct striking action.

In carrying out our invention the means for opening and closing the supply-ports of the engine-cylinder consist of a main valve and

20 an auxiliary valve, each having attached pistons driven by the motive fluid independently of the movement of the main piston and the two being with their respective ports and communicating passages organized to move

25 in alternation.

The object of the present improvement is to so time the movement of the main valve as to give a free and unrestricted supply of motive fluid to the back of the engine-cylinder

30 to drive its piston forward and a free and unrestricted exhaust at the front end of the cylinder without any cushioning of the piston until the piston reaches the point at which it brings the tool to the striking-point; and to

35 this end the invention consists in the construction of the main valve and the organization of the ports and passages of the engine-cylinder, hereinafter described and claimed, whereby the said object is accomplished.

40 In the accompanying drawings, Figure 1 represents a longitudinal vertical section of a coal-cutting machine embodying our invention, portions of the tool-carrying piston-rod and its guiding-sleeve being omitted as im-

45 material to the invention; Fig. 2, a plan of the engine-cylinder with the valve-chest and valves removed to expose the valve-seat and its ports to view; Fig. 3, a plan or back view of the main valve. The lines 1 1 in Figs. 2

50 and 3 indicate the line of section of Fig. 1.

Fig. 4 is a longitudinal vertical section of the engine-cylinder and valve-chest in the line 4 4 of Fig. 2; Fig. 5, a transverse vertical section in the line 5 5 of Fig. 4; Figs. 6 and 7, longitudinal vertical sections of the main valve and its seat in the same line as Fig. 1, but showing the valve in different positions; Fig. 8, a longitudinal section of the auxiliary valve and its seat.

a is the engine-cylinder; b, the piston; c, the tool-carrying piston-rod; d, the valve-chest containing the main valve e and the auxiliary valve f, working on seats g and h, arranged side by side on a plate i, which is affixed to the top of the cylinder a between it and the valve-chest and which contains the several valve-ports. The main valve e is moved and controlled by a piston J, the cylindric end portions of which work in the short single-ported cylinders k, provided in

65 the opposite ends of the valve-chest. The auxiliary valve f is moved and controlled by a piston l, the cylindric end portions of which work in the short single-ported cylinders m, provided in opposite ends of the valve-chest.

75 In the auxiliary-valve seat h there are three ports 10 11 12, viz: a central exhaust-port 10, communicating with the atmosphere through an opening (see Fig. 5) in the side of the cylinder, and two ports 11 and 12, the front port 80 11 communicating by a passage 14 in the plate i (see Fig. 2) with a port in the front end of the forward cylinder k of the main valve and the rear port 12 communicating by a passage 15 in said plate with a port in the rear end of 85 the rear cylinder k of said valve. The auxiliary valve f (shown in longitudinal section in Fig. 8) is an ordinary short D-valve capable of opening either one of the ports 11 12 to the motive fluid in the valve-chest and at the same time opening the other one to the exhaust-port.

90 In the main-valve seat g there are four ports 16 17 18 19. The central port 16 is an exhaust-port communicating with the atmosphere through the opening 13. The rear port 17 communicates, as shown in Figs. 1 and 4, with the engine-cylinder, near the rear end of the latter, through ports 20 21 and also communicates by a passage 22 in the valve- 95

100

plate (shown in Fig. 2) with a port in the front end of the forward cylinder *m* of the auxiliary valve. From the small front port 18 there is communication through a passage 23 (see Figs. 2 and 4) with the front end of the engine-cylinder *a*, and also communication through a passage 25 with the plate *i* (see Fig. 2) with the rear end of the rear cylinder *m* of the auxiliary valve. The larger front port 19 communicates by a passage 26 and ports 27 (see Figs. 1 and 2) with the engine-cylinder at a distance from its front end about equal to the length of the piston *b*. As will be presently fully explained, the port 18 and passage 23 are to the cylinder *a* only a supply-port and passage, and the port 19 and passage 26 and ports 27 only outlet-ports and passage. The main valve is of the short D type; but its exhaust-cove port 28 is made longer, so that, as shown in Fig. 6, which represents it at the middle of its stroke, the said cove-port may lap over parts of the port 17 and of both ports 18 19, and so open all the said ports at the same time to the exhaust-port 16, and said valve has also, as shown in Figs. 1, 3, 6, and 7, a long outside lap 24 at its front edge, which is of such width that in all positions, even in its rearmost position, (shown in Fig. 7,) the said valve closes the port 19, and so prevents any of the motive fluid from the valve-chest from ever entering the cylinder by the passage 26 and ports 27, though the said lap does not interfere with the exhaust through said ports and passage, because it does not extend to that part of the valve the section of which in Fig. 4 is taken in the line 4 4 of Fig. 2 through that part of the valve which works over the port 18.

We have shown in the drawings check-valves *n* applied in the inlet-passages of the engine-cylinder, and we have also shown a controller-valve chest *o* and controller-valve *p* outside of the main-valve chest, and we have also shown controlling-plugs *r* applied in the passages 22 25, which communicate with the outer ends of the auxiliary-valve cylinders *m*; but none of these devices are of themselves new or absolutely essential to our invention, though they may contribute to the most successful operation.

The relative operations of the main and auxiliary valves are as follows: When the main valve *e* and its piston *j* are at the forward end of their stroke, motive fluid from the chest will pass through the port 17 and passage 22 to the forward end of the auxiliary-valve cylinder *m*, and the rear end of the auxiliary-valve cylinder *m* will be open to exhaust through the passage 25 and ports 18 16. This will cause the auxiliary-valve piston *l* to move to its rear position, carrying with it the auxiliary valve *f*. The main-valve piston *j* will now receive the motive fluid in its front cylinder through port 11 and passage 14 and exhaust from its rear cylinder through passage 15 and the port

10 to the atmosphere and will be thrown backward. The motive fluid will now pass from the valve-chest through the forward port 18 and passage 25 to the rear auxiliary cylinder *m*, driving the auxiliary piston and valve forward and opening port 12, through which the motive fluid will pass by passage 15 and throw the main piston and valve forward again. These movements will continue alternately as long as the motive fluid is supplied to the valve-chest. Except, however, as to the long cove 28 and the lap 24 of the main valve *e* and the separate ports 18 19 in its seat and the two ports 20 21, through which the main seat-port 17 communicates with the engine-cylinder *a*, which we have hereinbefore described and the functions and operations of which we will proceed to explain, a similar system of valves is the subject of United States Patent No. 402,985.

It has been mentioned that the port 18 and passage 23 are to the front end of the engine-cylinder only an inlet and that the port 19, passage 26, and ports 27 are only outlet-ports and passage. This may be understood by reference to Figs. 1, 2, and 4. In Fig. 1 the main valve is at the forward end of the stroke and admits the motive fluid to the rear end 95 of the cylinder through port 17 and its branch ports 20 21, driving the piston *b* forward, the exhaust taking place in front of the piston through port 27, passage 26, port 19, valve-cove 28, and port 16. This exhaust is perfectly free until the piston *b* has moved to the point at which it closes cylinder-ports 27, which is the point at which the tool is intended to strike, after which the necessary slight cushioning and retardation of the piston will take 105 place. On the valve *e* making its return stroke the motive fluid will be admitted, as illustrated by Fig. 4, through port 18 and passage 23 to the front end of the cylinder and force the piston *b* backward, while the exhaust takes 110 place freely from the rear end of the cylinder through port 17 until the piston closes the cylinder-port 21, when the rearward cushioning of the piston takes place. During all this backward movement of the piston while 115 motive fluid is passing from the valve-chest to the front end of the cylinder through ports 18 and 23 it is prevented from entering the cylinder through ports 19 and 26 by the lap 24 on the front edge of the valve *e*, as shown 120 in Fig. 7, which represents the valve in the same position as in Fig. 4.

In the above-described operation the separate outlet-passage 26, with its ports 27 and 19, the outside front lap 24 of the valve *e*, and the wide cove 28 of said valve play important parts. The flow of the motive fluid into the valve-chest, regulated by a throttle-valve *q* or its equivalent, is more or less varied by the opening and closing of the ports leading to the engine-cylinder. As no resistance to the forward movement of the piston is made until after the tool strikes coal, the piston is free to move so rapidly forward that the pres-

sure in the valve-chest is slightly reduced, thus holding back or retarding the reversing of the main valve and allowing the piston to strike a very hard and effective blow. The retardation of the piston beyond where it closes the

5 exhaust-ports 27 then causes the pressure in the valve-chest to suddenly increase, and thereby reverse the valve *e* at the proper time, depending upon the distance of the

10 ports 27 from the end of the cylinder. By

the great length of the cove-port 28 of said valve, as illustrated in Fig. 6, which represents the valve moving forward, the exhaust

15 from one end of the cylinder *a* is caused to begin before the opening of the supply to the other end. This apparently forms communication between both ends of the cylinder;

but the piston being at one or other end of the cylinder when the valve should move

20 closes the port 21 or the ports 27, and so ex-

haust from both ends of the cylinder at the same time is prevented; but while the exhaust

25 at one end of the cylinder *a* is checked to provide for the cushioning of the piston an

30 advance and free exhaust is provided at the other end, and at the same time the pressure in the valve-chest is so increased as to throw the valve-pistons very quickly for reversing the valves and the movement of the piston *b*.

35 30. What we claim as our invention is—

1. In a direct-acting reciprocating engine, the combination with the engine cylinder and piston, of a valve-chest, a valve and a seat therefor in said chest, and a piston in said 35 chest for operating said valve, said seat having independent inlet and outlet ports for communication with the same end of the engine-cylinder and having an exhaust-port, said inlet-port communicating with said cyl-

40 inder near said end, and said outlet-port communicating with said cylinder at such greater distance from said end that its closure by the engine-piston before the completion of the stroke of the latter will time the reversal of

45 the valve, all substantially as herein described.

2. In a direct-acting reciprocating engine, the combination of a valve-seat having two

ports side by side one an inlet-port to one end of the cylinder and the other an outlet-port for the same end of the cylinder and having also an exhaust-port, and a slide-valve in which is a cove for communication between said outlet-port and the exhaust-port, and which has at one edge an outside lap of a width to cover the outlet-port without covering the inlet-port, substantially as herein described.

3. In a direct-acting reciprocating engine, the combination of a valve-seat in which are two ports leading respectively toward opposite ends of the engine-cylinder but communicating therewith at such distances from the ends thereof that their communication is closed by the engine-piston before completing its stroke, said seat also containing an exhaust-port intermediate to said two ports, and a slide-valve in which is a cove of a length to overlap both of said two ports and bring both into communication at the same time with the exhaust-port, substantially as herein described.

4. In a direct-acting reciprocating engine, the combination of a valve-seat in which is a central exhaust-port 16 and a port 17 having branches 20, 21 for communication with the cylinder at and near one end thereof and in which are also inlet and outlet ports 18, 19, communicating with the cylinder at and near the other end thereof, and a slide-valve 80 adapted to said seat and having a cove 28 and an outside lap 24, the said cove being of a length to form communication between both said ports 17, 19 and said lap being of a width to cover said outlet-port 19 without covering 85 said inlet-port 18, all substantially as and for the purpose herein described.

In testimony that we claim the foregoing as our invention we have signed our names, in presence of two witnesses, this 15th day of February, A. D. 1901.

HENRY C. SERGEANT.
WILLIAM PRELLWITZ.
